198,706

GARMENT DRYER

Charles E. Jennings, Jr., 4020 Simon Road,
Youngstown, Ohio

Filed Sept. 25, 1963, Ser. No. 76,726

Term of patent 14 years

(Cl. D49—1)

FIG. 1

FIG. 2

FIG. 4

FIG. 3

FIGURE 1 is a perspective view of a garment dryer, showing my new design;
FIGURE 2 is a top elevational view thereof;
FIGURE 3 is a front elevational view thereof; and
FIGURE 4 is a side view thereof.
The back is substantially plain.

I claim:
The ornamental design for a garment dryer, as shown and described.

References Cited in the file of this patent

UNITED STATES PATENTS

D. 193,805	Jennings	Oct. 9, 1962
2,815,585	Thompson	Dec. 10, 1957